Attorney.

UNITED STATES PATENT OFFICE.

VINCENT P. SOLLOW, OF PITTSBURGH, PENNSYLVANIA.

BOOK PROTECTOR.

Application filed March 12, 1929. Serial No. 346,439.

My invention relates to book protectors designed to be applied to books for the purpose of protecting the edges of the leaves of a book as well as the edges of the binding of a 5 book; and it is especially designed for use in protecting books while positioned on shelves and during the act of placing and/or removing a book from the book shelves.

The depreciation in the value of books, due 10 to dust and dirt settling on books is enormous, and is felt by publishers, book-sellers, librarians, and private owners and the like; and the amount of labor and expense involved in cleaning books that are positioned 15 on book-shelves is very considerable.

The prime object of the present invention is to provide a new and improved book protector or shield that may be readily applied to books, one that will be efficient in protecting 20 the books, and a construction that will not project from a book sufficiently to interfere in placing or removing a book from a book-shelf.

In the accompanying drawings, which illustrate an application of my invention:

Fig. 1 is a perspective view of a book showing my protector applied thereto;

Fig. 2, a perspective view of the protector embodying my invention;

Fig. 3, a sectional view taken on line III—III of Fig. 2;

Fig. 4, a sectional view taken on line IV—IV of Fig. 2;

Fig. 5, a side view showing a protector applied to the top and to the bottom edges of the book.

The protector as illustrated and as preferred comprises a shield formed of cardboard or other flexible material and includes 40 a folded member 5 having a centrally disposed depending portion 6 adapted to be inserted between the leaves of a book when the protector is applied thereto. Associated with the member 5 and telescopingly arranged therein is a member 7. Member 7 is provided with a downwardly extending portion 8 having at its lower end a folded portion 9. Said folded portion 9 has a projection 10 adapted, when the shield is applied to 50 a book, to enter the leaves at the side edges thereof.

A characteristic and important feature of the present invention resides in the telescoping members. These members provide means capable of adjustment whereby the 55 shield may cover the usually exposed top edges of the leaves, and/or as shown by Fig. 1, the top edges of the binding or cover; and extend downwardly to cover and protect the outside edge of the book. It is my intention 60 to provide a construction that may be of the proper size to fit inside of the top edges of the cover instead of projecting over the said edges, and it will be understood that the shields or protectors may be made in different 65 sizes to be employed with books of various sizes.

My protector is particularly adapted for the display of indicia on the exposed portions; for example, I have shown indicia at 70 11 on the downwardly projecting portion 8.

In the form of Fig. 5, I have shown a protector applied to the top and to the bottom edges of the book.

I claim:

1. A book protector comprising a shield having a telescoping upper portion comprising two members, one of said members having a portion for insertion between adjacent leaves of the book and the other member having a depending part adapted to project downwardly for protecting the outer edge of the book.

2. A book protector comprising a shield having a telescoping upper portion comprising two members, one of said members having a portion for insertion between adjacent leaves of the book and the other member having a depending part adapted to project downwardly for protecting the outer edge of the book, said depending part having a portion to enter between adjacent leaves of the book.

3. A book protector comprising a flexible shield having an adjustable telescoping top portion adapted to cover the upper edges of the leaves of a book and means associated with the telescoping portion for entrance between adjacent leaves of the book whereby the shield is retained in position on the book.

In testimony whereof I affix my signature.
VINCENT P. SOLLOW.
